By *Clarence O'Brien*,
Attorney

UNITED STATES PATENT OFFICE.

ISABEL M. DELLHEIM, OF CHICAGO, ILLINOIS.

CLOTHES-WASHING MACHINE.

Application filed December 28, 1927. Serial No. 243,065.

The present invention has reference to a clothes washing device which is especially adapted for use in connection with clothes boilers, or the like, wherein the device may be disposed and employed for creating a circulation of the boiling water through the clothes contained within the boiler, as well as providing means for preventing the liability of the clothes being scorched or otherwise damaged by contact with the heated bottom of the boiler.

One of the paramount objects of the device is to provide an attachment for clothes boilers of the character described, which may be adjusted for disposition within boilers of various sizes, and upon which the clothes to be boiled are placed and thus will be maintained in spaced relation with the bottom of the boiler, so that the same will be not scorched by contact therewith.

Another object is to provide such a device as this, which may readily be disassembled for the purpose of packing the same within a very small compass.

Other objects and advantages will become apparent as the device is better understood from the specification and claim to follow.

In the drawing:

Figure 1 represents a top plan view of the device.

Fig. 2 represents a vertical sectional view through the same, while

Fig. 3 represents a fragmentary sectional view, disclosing the manner of connecting the pair of plate sections.

Now for a more detail description of the invention reference is made to the drawings, in which like numerals designate like parts of the invention. A pair of perforated substantially elongated plates 1—1, have their associating ends substantially straight, while their opposite ends are curved at the corners 2, and from thence outwardly to provide semi-circular projections 3.

The plates are each curved transversely and the semi-circular projections are substantially of concavo-convex shape. The respective plates are curved downwardly at their longitudinal edge portions, while one of said plates has its opposite longitudinal edges curved downwardly and bent inwardly at 5, in spaced relation to its adjacent portion, so that the curved longitudinal edge portion of the complementary plate may en-

gage within the space thusly provided, for 55 slidably connecting said plates.

A hollow cup-shaped support 6 is adapted for disposition beneath one end of each plate. These cup-shaped supports are preferably circular and converged adjacent their top 60 portions to provide shoulders 7, upon which the edge portion of the respective projections 3 are adapted to rest.

The top portions of the respective cup supports are raised and formed in substantially 65 the same shape as the concave contour of the bulges as at 4. The bulged portion of each plate section is adapted to engage over the top portion of the respective cup-shaped supports, while its semi-circular edge portion 70 3 will rest upon the shoulder 7 of the support.

The supporting edge portion of the cup member is formed with a suitable number 75 of indentures 9, through which water will be admitted to the interior of the respective cup supports when the device is disposed within a conventional boiler, while at the top central portion of the respective cup supports, an opening 10 is formed.

A pair of tubes 11—11 are tubular and open at their lower ends. A cap 12 is provided for disposition upon the upper end of each tube, suitable means associated therewith, whereby the same will be clearly associated 85 with the tube when the device is in use, but which may readily be removed when it is desired to clean the respective tubes.

The tubes are formed with a multiplicity 90 of openings 13 arranged in longitudinal and circumferential spaced relation. The lower end portion of each tube is threaded at 14, and adapted to depend through the registering openings in the bulge 4, and top of the cup member, so that a jamb nut 15 threaded 95 inwardly on the threaded portion may engage the top surface of the bulge 4, while a second jamb nut 16 may be threaded on the end portion of the tube, and urged inwardly against the inner surface of the top of the support, for securing the tube in substantial 100 perpendicular relation to the bottom of the boiler in which this device is constructed for disposition.

When the plates have been properly associated with the supports and tube and connected in slidable relation with each other, the device is disposed within the boiler so

that the supports will rest on the bottom thereof.

The device may then be extended so that the supports will engage the ends of the boiler. Obviously, when clothes or any washable material is placed within the boiler and upon the plates 1—1, the same will be supported in spaced relation with the bottom of the boiler. Consequently, water poured 10 into the boiler will fill the space between the plates and the bottom of the boiler, so that when the same passes the boiling point, the boiling water will percolate upwardly through the tubes, 11 to spout onto the clothes 15 from the numerous openings 13.

The boiling water in passing downwardly through the mass of clothes, will cause the dirt and foreign matter collected therein to

be disintegrated, eventually to pass through the perforated plate for settlement upon the 20 bottom of the boiler.

Having thus described my invention, what I claim as new is:—

In a clothes washing device for disposition within a clothes boiler, a pair of hollow supports, each of said supports being provided with a tube through which water may flow and an inlet for water, a perforated plate supported at one end on each of said supports horizontally disposed, the longitudinal 25 marginal portions of the plates being transversely curved, and one of said plates being provided along its longitudinal edges with means for slidably receiving the other plate.

In testimony whereof I affix my signature.

ISABEL M. DELLHEIM.
